UNITED STATES PATENT OFFICE.

CHARLES GRIFFIN, OF YPSILANTI, MICHIGAN.

ASH REMOVER.

Application filed May 24, 1924. Serial No. 715,738.

To all whom it may concern:

Be it known that I, CHARLES GRIFFIN, a citizen of the United States, and a resident of Ypsilanti, in the county of Washtenaw and State of Michigan, have invented a new and Improved Ash Remover, of which the following is a full, clear, and exact description.

This invention relates to improvements in apparatus for removing ashes from stoves, furnaces and the like, and has for one of its objects the provision of an improved device of simple construction which will be effective in preventing the escape of dust during the operation of removing the ashes.

The above and other objects will appear more clearly from the following detailed description, when taken in connection with the accompanying drawing, which illustrates a preferred embodiment of the inventive idea.

In the drawing—

Figure 1 is a perspective view of the ash remover constructed in accordance with the invention;

Figure 2 is a longitudinal sectional view therethrough; and

Figure 3 is a horizontal section therethrough.

The device is shown as comprising a body portion 4 preferably supported on wheels 5 which permit of the device being readily moved from place to place. The body portion 4 is provided with an opening at its top adapted to be closed by a closure 6 hinged to the inner end of the body at 7. The discharge or other end of the body portion 4 is also provided with an opening 8 closed by means of the vertically swinging closure 9, the lower edge of which rests upon the rearwardly inclined portion 10 of the bottom of the body.

At the end of the body opposite the discharge opening 8 said body is provided with an inlet portion 11 reduced in width and capable of receiving in its outer end the discharge end of a chute or outlet from a stove, such as described for instance, in my co-pending application, Serial No. 715,737, filed May 24, 1924. Intermediate the ends of the portion 11 the same is provided with a flange 12 extending along the sides and bottom thereof so that when said chute is fitted therein, as shown in Figure 2, the flange 12 will aid in preventing the escape of dust

from the interior of the body 4. To further aid in maintaining the portion 11 in cooperative relation with the chute so as to prevent the escape of dust from the body, a supporting member 13 is pivoted at 14 to the bottom of the extension 11 adjacent its outer extremity and is engaged by a coil spring 15 which normally maintains the supporting member in a substantially vertical position, as shown in Figure 1. The movement of the member 13 to its normal position is limited by a flexible connection 16, one end of which is secured to the bottom of the portion 11 and the other end to the member 13, as shown in Figure 2. When the device is placed in operative position with respect to the chute the latter engages the member 13 and forces the same to a horizontal position against the tension of the spring 15 and said chute partially rests upon the member 13 while the ashes are being discharged into the body 4.

In order to facilitate the removal of the ashes from the body 4 a blade 17 is carried by a post 18 extending upwardly through the cover 6 and mounted for rotation therein. The upper end of the post is provided with a handle 19 which facilitates the rotation of the post when it is desired to operate the blade. Normally this blade is placed in a position substantially parallel with the sides of the body 4 and portion 11 so that said blade will not interfere with the entrance of the ashes into the body, but when it is desired to discharge the ashes from the body the blade 17 may be actuated to the position shown in Figure 3 after the closure 9 has been opened, so as to force the ashes from the body through the opening 8. It will be apparent that repeated operations of the blade in this manner will effectively cause the discharge of the major portion of the ashes from the body.

To facilitate the handling of the device the same is provided with a bail 20 pivoted to the body 4 adjacent its discharge end and having hingedly connected thereto at 21 the handle 22. This handle 22 is so connected to the bail that both the bail and handle may be folded upon the top of the device, as shown in Figure 1, when the device is not being used. The handle is formed at its connection with the bail with a small lateral extension 23 which, when the bail and handle are extended, engages the por-

tion of the hinge to maintain the bail and handle in substantially the same plane and limit the swinging movement of the handle with respect to the bail in one direction.

5. What is claimed is:

1. An ash remover including a body having inlet opening at its forward end and a discharge opening at its rear end, the former being capable of receiving the outlet end of a discharge pipe, and means pivotally mounted in said body for discharging ashes therefrom through said discharge opening.
2. An ash remover including a body having inlet opening at its forward end and a discharge opening at its rear end, the former being capable of receiving the outlet end of a discharge pipe, a cover for said body hingedly connected thereto, and pivotally mounted means carried by said cover and movable from a position longitudinally of said body to a position transversely thereof for discharging ashes through said discharge opening.
3. An ash remover including a body having inlet and discharge openings, the former being capable of receiving the outlet end of a discharge pipe, a cover for said body hingedly connected thereto, a post extending through said cover and mounted for oscillation therein, and a blade carried by the lower end of said post and operable when

oscillated to discharge ashes through said discharge opening.

4. An ash remover including a body having an inlet portion at one end and a discharge opening at its other end, the inlet portion being capable of receiving the outlet end of a discharge pipe, a spring-pressed supporting member engageable by said outlet pipe when the device is being positioned relative thereto to receive ashes therefrom and movable by such engagement to a supporting position, an oscillatory blade mounted in said body and movable to a position extending longitudinally of said body and also to a position transverse thereto to discharge the ashes through said discharge opening.

5. An ash remover, comprising a body supported on wheels and having a reduced front inlet end and a discharge opening at its rear end, a closure for the discharge opening, a vertical post pivotally mounted in the body and extending through the top thereof, said post being provided with a blade at its inner end and a handle at its outer end, a pivoted and spring pressed member at its inlet end, and means for supporting said member in a vertical position.

CHARLES GRIFFIN.
